IMPROVEMENT IN MACHINES FOR FELTING HAT BODIES.

PHILIP W. SOMERS, OF DANBURY, CONNECTICUT.

Letters Patent No. 60,274, dated December 4, 1866.

SPECIFICATION.

TO ALL WHOM IT MAY CONCERN:

Be it known that I, PHILIP W. SOMERS, of Danbury, in the county of Fairfield, and State of Connecticut, have invented new and useful improvements in Machinery for Felting or Sizing in Hat Bodies in the Roll; and I do hereby declare that the following is a full and correct description thereof, reference being had to the accompanying drawings, and to the letters of reference thereon.

My said improvements in machinery for felting or sizing hat bodies in the roll are especially adapted to work a new and improved roll, the subject-matter of a separate application for Letters Patent by me, wherein the said improved roll is more particularly described. For the purpose of this application it is deemed sufficient to describe said new roll generally as follows, to wit: that it is a roll of hat bodies within an enveloping or working cloth, similar to the roll ordinarily made by hatters in felting or sizing hat bodies in the roll by hand, except that the coils or folds of the bat or bats rolled up within the working or covering cloth are in a reverse direction from the coils or folds of the working or covering cloth instead of both being in the same direction, as in rolls used by hatters when felting or sizing in by the hand process, and heretofore used or attempted to be used in machines.

Figure 5, of the drawings, represents an end view of the old roll, the coils *a* of the hat body being in the same direction as the coils *b* of the working or covering cloth.

Figure 6, of the drawings, represents an end view of said new roll, the coils or folds *c* of the hat bodies being rolled up in a reverse direction from the coils or folds *d* of the working or covering cloth.

My said improvements in machinery are not adapted to working the old roll, but are especially designed for working said new rolls.

Figure 1, of the drawings, is a plan view.

Figure 2, a side elevation.

Figure 3, a longitudinal section; and

Figure 4, a cross-section of my improved machine.

My improvements in said machinery consist, first, in the arrangement and combination of a horizontal endless moving platform of grooved bars or grooved slats with two horizontal stationary adjustable yielding working beds, one above and the other below the endless platform, and with a yielding and adjustable concave located at one end of the endless platform, the whole arranged and constructed substantially as herein described; second, in combining with the lower working bed and the endless moving platform a sliding bed having two concave surfaces uniting in the middle, one of the concave surfaces, that next the endless moving bed, forming, in connection with the endless platform and lower bed, an adjustable throat or guide, whereby to introduce rolls of different sizes into the machine, the other concave being a receiving table for the rolls thrown out of the machine; third, in the employment of a throat-valve, located at the entrance of the throat of the machine, which, when closed, forms a bridge or inclined plane from the endless belt across the throat to the receiving table, and operates to throw out the rolls from the machine and guide them to the receiving table; and, when open, permits the entrance into the machine of new rolls, and also guides the rolls that have passed around the endless table into the throat to be again passed through the machine; fourth, in combining with the lower bed transversely grooved rubbing surfaces, having side-water ways or channels, to receive and carry off from the machine the water expressed from the bodies.

But to more particularly describe the construction and operation of my improved machine, I will refer to the drawings by letters of reference. In the frame, *d*, of the machine I place suitable shafts and drums, *e*, to carry the endless moving table, which is constructed of light wooden grooved bars, *e*, wired or otherwise secured to endless belts or chains, *e*, carried by the drums. A driving-pulley, *e*, may be used to impart motion to the endless working table, which has a continuous forward motion in the direction of the arrows. A horizontal bearer or guide, *f*, projecting inwards from the side rail of the frame that supports the drums, forms a guide and support between the drums for the endless working table against the pressure of the rolls. Friction rollers may be placed in the bearing surfaces of the guide, *f*. The lower yielding adjustable bed I make in two parts, *g*, connected together by a plate, *g*, on each side of the bed at the middle of the machine, to which plates the two parts of the bed are hinged by suitable pivots, *g*, so that the middle of the bed may be depressed to compensate for the sagging of the lower member of the endless working table. The middle of the bed is

supported by four bent springs, $g^6 g^8 g^7 g^9$, two on each side of the machine; chains, g^9 , depend from each of the connecting hinge plates of the bed, by which the middle of the bed can be depressed against the pressure of the supporting springs, and then held in place by hooks, $g^{10} g^{11}$, on the inside of the frame, on which the chains are hooked for that purpose. The floor, g^{12} , of the lower working bed is made of short boards finely grooved, like a wash-board, transversely to the line of travel of the endless bed, and secured in the side timbers of the frame of the bed, which are rebated to receive the grooved floor boards; and tied together by cross-planks, $g^{13} g^{14}$; gutters or channels, $g^{15} g^{16}$, run along each side of the bed, connecting with pipes, g^{18} , to conduct the water expressed from the bodies away from the machine.

There are four round guide-rods, $h h^1 h^2 h^3$, attached to the lower side of the lower bed, which fit loosely in corresponding holes in the cross-planks, $i i$, of the frame, and around which are coiled helical springs that support the ends of the bed with yielding pressure. The lower bed may be adjusted at either end at a greater or less distance from the endless bed by means of the two levers, $j j^1$, one at each end of the machine below the bed. These levers are each connected by links, j^2 , with the bed, at the middle of the lever, one end of each lever being confined to one side of the machine by a staple, j^3 , or other fulcrum joint, and the other end projecting out from the other side, where it is secured in the desired position by a catch, j^4 . The upper bed or platform is a plain plank or board, k , loosely suspended at four points from the cross-bars, $k^1 k^2$, of the frame by means of four helical springs, $l l^1 l^2 l^3$, which permit the suspended bed to yield in any direction. The bed may be as well suspended by leather straps, the object being to permit it to yield a little in any direction to accommodate the working of the rolls. A weight may be placed on the upper side of this bed to make pressure, if desired; and the lifting of the board by the pressure of the roll may be restrained and regulated by a hooked link, m , connected with the frame of the machine above the bed, which may be extended so as to hook into the different staples, $m^1 m^2 m^3 m^4$, on the top of the bed. The concave, by means of which the rolls are transferred from the lower to the upper side of the endless bed, is composed of two sections, both of them grooved like the lower bed. The lower section, n , of the concave is backed up by springs, n^1 , which are placed between it and the standards, $n^2 n^3$, rising from the lower bed, which support the concave. The upper section, o , of the concave is held by arms, $o^1 o^2$, hinged to the standards, $n^2 n^3$, and kept in place with yielding pressure by the bent springs, $o^3 o^4$. The concave, being supported by standards rising from the frame of the lower bed, moves up and down with it whenever it is raised and depressed for the purpose of adjustment to different sizes of rolls. To prevent throwing the concave out of proper adjustment when the lower bed is raised or lowered, inclined guides, $p p^1 p^2 p^3$, formed of round rod iron, bent into the shape shown in the drawing, are placed upon the front and rear posts of the frame of the machine, and the bed connected with the guides by eyes or staples surrounding the guides and driven into the frame of the bed; the bed, having sufficient end play for the purpose by reason of its vertical guides within the helical springs fitting their sockets loosely, is thrown backward or forward, according as it is elevated or depressed, sufficiently to keep the concave which moves with it in proper adjustment with the endless table, so that it will not fail to carry up the rolls to the upper side of the endless table. A sliding bed, q , rests on that part of the lower bed which projects from the front of the machine, and slides on it towards and from the endless working bed. On the upper surface of the sliding bed, q , are two concave surfaces, inclining in opposite directions from the line where they meet, and extending to the opposite ends of the sliding bed. One of these inclined surfaces or beds, r , that next to the endless table, is a plain surface, and forms an inclined throat or shoot, down which the rolls are carried into the machine by the endless band. The other inclined concave, s , is a receiving table for the rolls that are discharged from the machine. It is corrugated for the purpose of retarding the motion of the roll as it comes from the machine. A stop, s^1 , prevents the rolls from rolling off the table.

The object of having the sliding bed move on the lower bed is to adjust the throat to various sized rolls. The throat-valve, t , swings on suitable centre pins, and is like the throttle-valve of a steam engine, except that it is rectangular instead of circular. When in position to form a bridge over the throat to throw out the rolls, it may be held there by a button, u ; when it is desired to let the rolls pass again around the machine, the valve may be put in position shown in red lines v in the drawings; when the rolls are introduced, the valve is turned to the position shown by red lines w in the drawings. In the use of this machine, the hatter, being at the sizing kettle, which should be placed immediately in front of the machine, has the valve at his command; that is, he can take hold of it with his hand and turn it to the position desired for the moment. Having made the roll of bats and covering cloth, as herein described, he throws the roll into the throat of the machine, where it is taken hold of by the endless bed and rolled continuously between it and the surrounding yielding adjustable surfaces formed by the lower bed, concave, and upper bed, until the hatter desires to examine it, when he turns the throat-valve across the throat and throws out the roll or rolls that are in the machine. The machine is designed to work as many rolls at once as can be carried around in it or can be properly attended to by the hatter or hatters in front.

It will be observed that in the use of this machine the roll must be put into the machine with the coils of the covering cloth running in the direction of the motion of the drums and band, so that the rolling in the machine will keep the coils of covering cloth wound up instead of stripping off the cloth by unrolling it. There being no back or reverse rolling action in this machine, the motion under pressure is all applied in the direction applied in hand working when my new or reverse roll is used in the machine. If the old roll is used, the machine will not work the roll to the satisfaction of the hatter, or as well as machines having the vibrating or reverse motion combined with the forward motion, because those machines give part of their motion under pressure in the right direction for the old roll, although the necessity of keeping the covering cloth wound

up on the roll compels the greater part of their motion under pressure to be given in the wrong direction for the old roll.

I claim as my invention and improvement in machinery for felting or sizing in hat bodies in the roll—

1. In combination with the endless moving platform of grooved bars or slats the stationary yielding adjustable lower bed, concave, and upper bed, the whole constructed and arranged to yield and be adjusted, substantially as described.

2. In combination with the lower bed and endless moving bed the sliding bed with its two inclined concaves, one of them forming, in connection with the endless platform, an adjustable throat, and the other being a receiving table to receive the rolls thrown out of the machine.

3. The valve located at the entrance of the throat of the machine, in combination with the endless bed, throat, and receiving table, substantially as described, and for the purposes set forth.

P. W. SOMERS.
